UNITED STATES PATENT OFFICE.

FRANK E. MARCY, OF SALT LAKE CITY, UTAH, ASSIGNOR TO FRANK KLEPETKO, OF NEW YORK, N. Y.

ROASTING-FURNACE.

No. 920,971.

Specification of Letters Patent.

Patented May 11, 1909.

Application filed March 20, 1909. Serial No. 484,737.

To all whom it may concern:

Be it known that I, FRANK E. MARCY, a citizen of the United States, residing at Salt Lake City, in the county of Salt Lake 5 and State of Utah, have invented certain new and useful Improvements in Roasting-Furnaces, of which the following is a full, clear, and exact description, reference being had to the accompanying drawings, forming a part hereof.

My invention has relation to improvements in roasting-furnaces; and it consists in the novel details of construction more fully set forth in the specification and 15 pointed out in the claims.

In the drawings, Figure 1 is a vertical middle section and part elevation of a portion of a rabble-shaft and arms constituting my invention, and showing its application to a roasting furnace; Fig. 2 is an enlarged vertical section on line 2—2 of Fig. 3 showing the connection between the shaft and rabble-arm, and showing one form of my invention; Fig. 3 is a cross-section on 25 line 3—3 of Fig. 2; Fig. 4 is a horizontal section on line 4—4 of Fig. 3; Fig. 5 is a sectional detail on the order of Fig. 2 showing a modified construction; and Fig. 6 is a similar section showing still another modification.

The object of my invention is to provide an air jacket for the rabble-shaft and rabble-arms of roasting furnaces, especially for rabbles used in the treatment of ores whose 35 fuel contents is so proportioned that an abnormal absorption of the heat units generated by its combustion, by the cooling medium circulating through the shaft and arms becomes detrimental to the successful 40 operation of the furnace.

In furnaces employing water as a circulating medium for the rabble-shaft and arms, before the necessary cooling of the rabble apparatus can be effected, the water must 45 necessarily abstract so large a percentage of heat units from the charge, that an undue reduction of temperature results, and the roasting becomes incomplete. My present arrangement contemplates the interposition 50 between the parts through which the water circulates and the ore, of a jacket of air, so that the water will not come in direct contact with the walls which are in immediate contact with the charge. This arrangement 55 will necessarily cut down the amount of

water used on account of the heat non-conducting qualities of the interposed air envelop or jacket and consequently increase the capacity of the furnace. At the same time the walls of the rabble apparatus are 60 kept sufficiently cool to prevent sagging and deterioration from the heat to which they are subjected in the furnace.

In detail the invention may be described as follows:

Referring to the drawings and particularly to Figs. 1 to 4 inclusive, F represents a furnace in dotted outline, being of a conventional type and well understood. The hearths are represented by h, the material or charge 70 dropping from one hearth to the next hearth below as is well understood in the art. Passing through the several hearths is the rotatable hollow rabble-shaft 1, from which radiate the series of hollow arms 2 extending into 75 the several hearths and carrying rakes 3 by which the material is successively fed from one hearth to the hearth immediately beneath it, all as fully understood in the art. Circulation through the hollow shaft and 80 arms of a suitable cooling medium (preferably water) may be effected in any way known to the art; and in the drawings I have shown in dotted outline a water-feed pipe 4 having distributing pipes 5 leading 85 and opening into the hollow arms from which the water is discharged and passing through the arms flows back into the shaft around the pipe 4 and eventually up and out through the shaft. This method of circulation, however, is well understood and is 90 merely cited here as one of the many that might be resorted to, to effect cooling of the rabble apparatus. Formed between the exterior wall of the shaft and the wall of the 95 passage through which the water circulates is an air jacket 6; and formed between the exterior wall of the rabble arm and the wall of its water passage is an air-jacket 7, the two jackets having no intercommunication in 100 the forms shown in Figs. 1 to 4 inclusive, since it is desirable and preferable to keep the outer wall of the hub or 'boss' 1' to which the arm is attached, water cooled, as most strength must be centered in this particular 105 member.

In the modification shown in Fig. 5, the air-jacket 6 is continued around the hub in the form of an extension 6' but separated from the jacket 7 of the rabble arm. In the 110

modification shown in Fig. 6 the air-jacket 6" of the hub is in direct communication with the jacket 7 of the arm. These modifications may be used where the heat developed in the charge is not too great to have any detrimental effect on the hub.

For the majority of cases in constructions of the character here described, the water or equivalent cooling medium abstracts sufficient heat units from the rabble apparatus to keep the same at a sufficiently low temperature to resist the disintegrating and destructive effects of the heat of the furnace. The air-jacket of course acts as an intercepting layer between the water and the heated products of the furnace, thus preventing the water from abstracting the heat units of the charge to a point where the furnace ceases to give proper results. Where the inner cooling and circulating medium is water, of course the air-jacket is not in communication with the interior passages of the rabble shaft or arms; but where air is employed the air-jackets may be made to communicate with such inner passages, though not necessarily.

Of course I do not wish to restrict the application of the rabble apparatus to ore-roasting furnaces as it may be employed in any art where it can find suitable application.

Having described my invention, what I claim is:

1. In a furnace, a hollow rabble-shaft through which is adapted to circulate a cooling medium, and an air jacket forming the enveloping walls of said shaft, substantially as set forth.

2. In a furnace, a hollow rabble-shaft and hollow arms therefor, means for circulating a cooling medium therethrough, and outer air-jackets enveloping the shaft and arms respectively, substantially as set forth.

3. A rabble apparatus comprising a hol-

low shaft and hollow arms radiating therefrom, means for circulating a cooling medium through said shaft and arms, and air-jackets enveloping the passages of the shaft and arms but not in communication therewith, substantially as set forth.

4. A rabble apparatus comprising a hollow shaft and hollow arms radiating therefrom for the circulation of a cooling medium, and an air-jacket enveloping the passages of said shaft and arms, the jackets of the arms being in communication with the jacket of the shaft, substantially as set forth.

5. A rabble apparatus comprising a hollow shaft and hollow arms radiating therefrom for the circulation of water therethrough, and air jackets separating the walls with which the water contacts, from direct contact with the furnace charge, substantially as set forth.

6. In a rabble apparatus, a hollow rabble arm having an outer air-jacket, substantially as set forth.

7. In a rabble apparatus, a hollow rabble arm having an air-jacket enveloping the same, but not in communication with the interior of the arm, substantially as set forth.

8. A rabble shaft having an inner passage for the circulation of a cooling medium, and an outer non-communicating air-jacket, substantially as set forth.

9. In a rabble apparatus, a hollow member having a passage-way for the circulation of a cooling medium, and provided with an air jacket contiguous to said passage-way.

In testimony whereof I affix my signature, in presence of two witnesses.

FRANK E. MARCY.
